CONTAINER FOR BABY BOTTLES AND THE
LIKEIsaac Lieber, New York, N. Y., assignor to Thervac
Products, Inc., New York, N. Y., a corporation
of New York

Application February 3, 1939, Serial No. 254,414

3 Claims. (Cl. 229—14)

This invention relates to new and useful improvements in a container for a baby's bottle or the like.

The invention proposes the construction of a container for a baby's bottle or the like characterized by a hollow cylindrical body having a closed bottom end and upon which a hollow cylindrical cover is adapted to be engaged for completely encasing a baby's bottle which has been inserted into said cylindrical body.

Specifically, it is proposed to provide the open end of said hollow cylindrical body with an annular member securely clamped thereon in a manner to receive the top edge of a corrugated sheet for holding the same spaced from the interior wall of said body.

Still further it is proposed to mount insulating material in the space between the adjacent faces of said corrugated sheet and the inside wall of said body in a manner to insulate said body to keep the contents of the bottle warm or cold, as desired, for a considerable length of time.

Another object of this invention is the construction of a device as described, which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure—

Fig. 1 is a perspective view of a container for a baby's bottle or the like constructed according to this invention.

Fig. 2 is a vertical sectional view on the line 2—2 of Fig. 1.

Fig. 3 is a horizontal sectional view on the line 3—3 of Fig. 2.

Fig. 4 is a perspective view of the heat insulating material and corrugated sheet per se.

The container for a baby's bottle or the like, according to this invention, comprises a hollow cylindrical body 10 having a closed bottom end and an open top end for permitting a baby's bottle or the like to be inserted. The hollow cylindrical body has a double wall consisting of an inner wall section 10a and an outer wall section 10b. The wall sections are constructed of cardboard or similar material, preferably pasted together, and the top edge of the inner wall section 10a extends beyond the top edge of the outer wall section 10b. A bottom wall 11 is provided

for closing the bottom end of the hollow cylindrical body 10. This bottom wall 11 is of a diameter equal to the outside diameter of the inner wall section 10a and is rested there-against as shown in Fig. 2. The bottom edge 10b of the outer wall section 10b is turned under and engages the bottom face of the bottom wall 11 for rigidly maintaining the same in position against the bottom end of the inner wall section 10a. The bottom wall 11 may be secured in any other manner.

A hollow cylindrical cover 12 engages over the top end of the hollow cylindrical body 10 for completely encasing the bottle inserted into the body 10. The hollow cylindrical cover 12 is formed of cardboard or similar material and is of a diameter substantially equal to the diameter of the outer wall section 10b of the hollow cylindrical body 10. In engaging the hollow cylindrical cover 12 upon the body 10 the same engages around the periphery of the inner wall section 10a and is passed thereover in end alignment with the outer wall section 10b as shown in Fig. 3.

A means is provided for closing the top end of the hollow cylindrical cover 12. This means comprises a top wall 13 having an outer diameter equal to the inside diameter of the hollow cylindrical cover 12. The top edge 12a of the hollow cylindrical cover 12 is bent inwards and engages the top face of the top wall 13 for holding the same in position within the cylindrical cover 12. The top wall 13 may be secured in any other way.

An annular member 14, of metal or other similar material, is mounted on the top end of the inner wall section 10a of the hollow cylindrical body 10 and forms an inwardly extending flange. The outer edge portion of the annular member 14 is formed with a groove 14a (see Fig. 2), the material of which is tightly clamped upon the edge of the inner wall section 10a. The top edge portion of the inner wall section 10a is slightly compressed for permitting the outer edge portion of the groove 14a to remain substantially flush with the outside face of the wall of the section 10a so that the cover 12 may be engaged thereon.

A corrugated disc 15 is rested upon the inner face of the bottom wall 11 forming a plurality of air spaces 16 between the adjacent faces of the disc 15 and the bottom wall 11 for insulating the inside of the hollow cylindrical body 10 from the outside thereof. A corrugated sheet 17 is engaged within the hollow cylindrical body 10 and has its face spaced from the adjacent face of the inside of the hollow cylindrical body 10. The

- bottom end of the corrugated sheet 17 rests upon the top face of the corrugated disc 15. The inner edge portion of the annular member 14 is formed with a flange 14b behind which the top edge of the corrugated sheet 17 extends in a manner to hold the corrugated sheet axially of the cylindrical body 10 to maintain the space between the adjacent faces of the sheet 17 and the cylindrical body 10.
- 10 In constructing the container the insulating material 18 is securely attached to one face of the corrugated sheet 17 and is adapted to be placed into the container at the same time the sheet is engaged therein. The insulating material is secured thereto for maintaining the same extended along the entire length thereof and for preventing it from sliding downwards within the space between the adjacent faces of the sheet 17 and the body 10.
- 15 20 The operation of the device is as follows: The milk or other substance to be placed within the bottle is put therein and the entire bottle is heated, or cooled, and then placed within the container through the open end of the hollow cylindrical body 10. The hollow cylindrical cover 12 is engaged thereon for completely sealing the interior of the container from the outside atmosphere for keeping the contents of the bottle warm or cold until such time as it is needed.
- 25 30 While I have illustrated and described my invention with some degree of particularity, I realize that in practice various alterations therein may be made. I therefore reserve the right and privilege of changing the form of the details of construction or otherwise altering the arrangement of the correlated parts without departing from the spirit or the scope of the appended claims.
- 35 40 Having thus described my invention, what I claim as new and desire to secure by United States Letters Patent is:
1. In a container for baby bottles and the like, a hollow cylindrical body having a closed bottom end, a corrugated disc rested on said closed bottom end, an annular member mounted on the top end of said body and extending radial inwards and at its inner edge having a longitudinally inwardly extending flange portion, and a tubular heat insulation unit comprising flexible heat insulation material adjacent and extending around the side wall of said body and

at its top stopping short of said flange and a flexible sheet extending along said heat insulation material and at its bottom edge resting on said disc and at its top edge projecting above said heat insulation material and behind said flange portion and having free side edges adjacent each other, whereby one of said side edges may be gripped and pulled for easily removing said heat insulation unit.

2. In a container for baby bottles and the like, 10 a hollow cylindrical body having a closed bottom end, an annular member mounted on the top end of said body and extending radial inwards and at its inner edge having a longitudinally inwardly extending flange portion, and a tubular heat insulation unit comprising flexible heat insulation material adjacent and extending along the side wall of said body and at its top stopping short of said flange and a flexible sheet 20 extending along said heat insulation material and at its bottom edge resting on said disc and at its top edge projecting above said heat insulation material and behind said flange portion and having free side edges adjacent each other, whereby one of said side edges may be gripped and pulled for easily removing said heat insulation unit, said heat insulation material and flexible sheet being pasted together as a unit.

3. In a container for baby bottles and the like, 30 a hollow cylindrical body having a closed bottom end, a corrugated disc rested on said closed bottom end, an annular member mounted on the top end of said body and extending radial inwards and at its inner edge having a longitudinally inwardly extending flange portion, and a tubular heat insulation unit comprising flexible heat insulation material adjacent and extending around the side wall of said body and at its top stopping short of said flange and a flexible sheet 40 extending along said heat insulation material and at its bottom edge resting on said disc and at its top edge projecting above said heat insulation material and behind said flange portion and having free side edges adjacent each other, 45 whereby one of said side edges may be gripped and pulled for easily removing said heat insulation unit, said heat insulation material and flexible sheet being pasted together as a unit, and said flexible sheet being of corrugated material. 50

ISAAC LIEBER.
